DRAWING KIT

Filed June 25, 1928

UNITED STATES PATENT OFFICE

JUSTIN R. SWIFT, OF CHICAGO, ILLINOIS, ASSIGNOR TO THE SUPERIOR TYPE COMPANY, OF CHICAGO, ILLINOIS, A CORPORATION OF ILLINOIS

DRAWING KIT

Application filed June 25, 1928. Serial No. 288,173.

My invention relates to portable drawing boards and particularly to an improvement on the construction shown in my copending application Serial No. 194,107 filed May 25,

5 1927.

An object of my invention is to provide a complete and compact drawing kit of a new and improved design, in which I utilize a box or container of relatively rectangular shape 10 and having a sliding drawer therein adapted to contain various drawing papers and equipment.

Means are provided on this box for retaining a sheet of paper in flat position on the top 15 of the box, as well as to receive a tablet.

In a device of this character the most important requisites are suitable size and weight, with provision for carrying materials and means for insuring comparatively accurate 20 drawings with a T-square and triangles.

In my present improvement I have incorporated means for insuring a more rigid construction of the box as well as means for insuring a more uniform and even bearing 25 surface for the T-square.

A further improvement in my present device relates to the means for securing the drawer within the box, whereby the box may be inserted and removed with the utmost 30 facility at all times.

The invention will be more readily understood by reference to the accompanying drawing, in which—

Fig. 1 is a plan view partly in section of 35 my improved drawing kit;

Fig. 2 is a transverse sectional view of my improved device on the line 2—2 of Fig. 1;

Fig. 3 is a side view showing the aperture in the side wall and the drawer clip therein, 40 and

Fig. 4 is a sectional view slightly enlarged on the line 4—4 of Fig. 1.

By reference to the drawing it will be seen that I have provided a rectangular metal box 45 having top and bottom walls 10, 11, respectively, end walls 12, and an indented side wall 13. The edge of the bottom wall 11 is doubled back on itself as at 14 and the edge of the top wall is bent back as at 15. A longitudinal bead 16 is formed in the metal of

the top wall near the margin for the purpose of providing stiffening supplemental to the double thickness edge and for another purpose later to be described.

At the opposite side as best shown in Fig. 55 4, I provide so-called beads 17, 18, formed from the material composing the wall 13 and located at the upper and lower extremities of box, extending longitudinally thereof. These beads are so arranged that the wall 13 is indented 60 and acts as a stop for the side wall 19 of the drawer. The particular purposes for the peculiar back wall arrangement are, first, the provision of a limited area of contact for the head A of a T-square and second, to so arrange 65 the back wall that the drawer does not contact or serve to distort the portion with which the T-square head contacts. It has been found to be extremely difficult to so arrange the back wall of a box of this character 70 that the area for contact with the T-square head shall remain uniform and a plane surface under the stress of manufacturing conditions. Due to the necessity for utilizing relatively very thin gauge metal, there is like- 75 lihood of distortion even after production on perfect dies, either by handling during manufacturing or subsequent use or due to warping by the heat necessary to bake on the enamel used for covering. I have, therefore, 80 eliminated these sources of trouble by constructing the area of contact by the T-square of generally channel shape and of comparatively small cross sectional size. This insures 85 stiffness and rigidity without distortion by the heat of subsequent operations and, by providing a drawer stop apart from the area of contact by the T-square, that trouble is eliminated.

The drawer may be of any desired form 90 having a floor 20, partitions 21, and front wall 22. The drawer is intended to receive drawing materials and a pad of paper resting on the top of the partitions. In withdrawing the drawer, there is a tendency for the upper sheets of the pad of paper to catch on the inturned edge 15 of the top wall and this is obviated by providing the bead 16 in close proximity thereto.

As a means for securing the drawer in 100

place and for facilitating its ejection from the box, I provide a finger hole 23 in the wall 13, the hole being located substantially midway between the ends of the box. The fastening clip consists of a spring tongue 24, riveted or welded to the floor of the drawer and having a hook 25 formed near its end terminating in an upstanding arm 26, the arm and hook projecting through the aperture 23 in the back wall of the box. The end of the portion 26 is located at substantially the center of the hole 23, and pressure by the finger, on the arm, serves to rock it sufficiently to elevate the lock 25 out of engagement with the catch 23A located in a plane with the wall 13; continued pressure on the arm will cause the finger to contact the back wall 19 of the drawer, and serve to push the drawer out of the box. Thus the action of unlatching the box serves to also push the drawer out.

In the top wall 10 of the box and located near the rear margin thereof are three narrow longitudinal slits 27. These slits are located sufficiently close to the rear margin or back wall of the box, so that they are not above the drawer and any dirt or moisture that may drop through the slits will not drop in the drawer. The slits are intended to receive the paper holding bands or clips 28, having at one end a hook 29 adapted to enter a slit and at the other end a rebent resilient portion 30. The clips are composed of spring metal and normally occupy a bowed position as indicated in dotted lines in Fig. 2. However, when a sheet of paper or a card are to be held in place on the top of the box, they are placed in position as indicated in Figs. 2 and 4; the hook 29 inserted in a slit 27, and the opposite end pushed downward until the end 30 engages beneath the free edge of the top wall. Due to the construction of the clip and the cooperating parts, the clip will function whether the drawer is closed as shown in Fig. 2 or partly open as indicated in dotted lines in Fig. 1. By the provision of three equally spaced slits and elongating the slits to the extent indicated, I am able to hold in place comparatively small cards or large sheets of paper as required.

Another purpose for the slits is to provide for cooperation therewith of tongues or lugs on a metal back for a pad of paper. This is described and claimed in detail in a co-pending application and is not specifically disclosed and claimed herein. For convenience in handling, the T-square, spring clips, pad of paper and other drawing equipment, all are intended to be received within the drawer.

In order to insure a tight fit of the drawer when in closed position without too close fitting of the parts, I provide at the back edge of the box and fixed to the upper wall a wedge member 31 so placed that the rear end 65 of the drawer is caused to contact the same

and force the drawer into tightly held relation when in locked position.

It will be noted that the wall containing the finger opening and the spring catch is located well within the limits of the box so that the catch does not project outside of the walls. There is, therefore, no likelihood of accidental actuation of the catch by contact with exterior objects.

The back wall construction not only provides a rigid plane surface for contact by the T-square head, but insures the maintenance of this surface notwithstanding relatively rough handling of the box and the hammering of the drawer in being returned to its closed position. The pockets provided by the beads serve to trap air and insure somewhat of a limited cushioning effect even though the drawer be carelessly returned.

Other modifications and variations may be made in the construction shown, and I do not wish to be limited except as indicated in the appended claims.

I claim:

1. In combination, a metal box and a drawer slideable therein, the top wall of the box being adapted for use as a support for drawing paper, a side wall of the box being shaped to provide a narrow continuous plane surface near the said top wall for engagement by the head of a T-square and a relatively indented portion adapted to act as a stop for said drawer. 90

2. In combination, a metal box and a drawer slideable therein, the top wall of the box being adapted for use as a support for drawing paper, a side wall of the box being shaped to provide a narrow, continuous bead near said top wall and adapted to furnish a continuous plane surface of limited area for sliding engagement by the head of a T-square, another portion of said side wall being positioned relatively inwardly of said bead to act as a stop for said drawer. 100

3. In combination, a metal box and a drawer slideable therein, the top wall of the box being adapted for use as a support for drawing paper, a side wall of the box being shaped to provide a pair of channel shaped beads, one wall of each of which channels is co-extensive with the top and bottom walls of the box, the metal wall connecting the channels acting as a stop for said drawer. 110

4. In combination, a metal box and a drawer slideable therein, the top wall of the box being adapted for use as a support for drawing paper, a side wall of the box being shaped to provide a pair of channel shaped beads, one wall of each of which channels is co-extensive with the top and bottom walls of the box, the metal wall connecting the channels acting as a stop for said drawer, said last named wall having a finger opening, and a drawer-catch projecting through said opening. 120

5. In a drawing kit, the combination of a box having top, bottom, and end walls and one side wall, a drawer adapted to slide into the box through an open side, said side wall
5 having a finger opening located midway between the ends, and a spring catch fixed to the drawer and adapted to hook over the material surrounding said opening, a portion of the catch projecting across said opening,
10 whereby pressure exerted on said catch acts first to release the catch and then to dis-
place the drawer.

6. In a drawing kit, the combination of a box having top, bottom, and end walls and
15 one side wall, a drawer adapted to slide into the box through an open side, said side wall having a finger opening located midway between the ends, and a spring catch fixed to the drawer and adapted to hook over the material
20 surrounding said opening, a portion of the catch projecting across said opening, where-
by pressure exerted on said catch acts first to release the catch and then to displace the drawer, the portion of side wall containing
25 the opening being located in a plane a sub-
stantial distance inside of the limits of the box.

In testimony whereof I have affixed my
signature.

JUSTIN R. SWIFT.
